US00D990208S

(12) **United States Design Patent** (10) Patent No.: **US D990,208 S**
(45) Date of Patent: **** Jun. 27, 2023**

(54) **DISPLAY STAND**

- (71) Applicant: **Apple Inc.**, Cupertino, CA (US)
- (72) Inventors: **Sheng Yang**, Mountain View, CA (US); **Olivia M. Ching**, Austin, TX (US); **Chien Tsun Chen**, Taipei (TW); **Eric Weijia Wang**, Newark, CA (US); **Ricardo A. Mariano**, Hayward, CA (US); **Allison Inouye**, San Francisco, CA (US); **Kristy Judy Hsu**, San Jose, CA (US); **Po Huang**, San Jose, CA (US); **Jean-Marc Gady**, Los Altos, CA (US); **Peter Russell-Clarke**, San Francisco, CA (US); **Daniele De Iuliis**, San Francisco, CA (US); **Jeremy Bataillou**, San Francisco, CA (US); **Markus Diebel**, San Francisco, CA (US); **Rico Zörkendörfer**, San Francisco, CA (US); **Molly Anderson**, San Francisco, CA (US); **Shota Aoyagi**, San Francisco, CA (US); **Jody Akana**, Los Altos Hills, CA (US)
- (73) Assignee: **Apple Inc.**, Cupertino, CA (US)
- (**) Term: **15 Years**
- (21) Appl. No.: **29/842,401**
- (22) Filed: **Jun. 13, 2022**

(57)

CLAIM

The ornamental design for a display stand, as shown and described.

DESCRIPTION

FIG. 1 is a top front perspective view of a display stand showing the claimed design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a top front perspective view thereof showing the claimed design in an environment in which it may be used; and,
FIG. 9 is a bottom rear perspective view thereof.
(Continued)

The broken lines in the figures show portions of the display stand and environment that form no part of the claimed design.

1 Claim, 8 Drawing Sheets

Related U.S. Application Data

continuation of application No. 29/807,507, filed on Sep. 13, 2021, now Pat. No. Des. 945,803, which is a continuation of application No. 29/758,623, filed on Nov. 17, 2020, now Pat. No. Des. 930,414, which is a continuation of application No. 29/743,203, filed on Jul. 20, 2020, now Pat. No. Des. 904,091, which is a continuation of application No. 29/695,817, filed on Jun. 21, 2019, now Pat. No. Des. 893,926.
